UNITED STATES PATENT OFFICE.

HENRY A. WEIHMAN, OF PHILADELPHIA, PENNSYLVANIA, ASSIGNOR TO
SIMONS BRO. & CO., OF SAME PLACE.

DESIGN FOR A HANDLE FOR NAIL-FILES, &c.

SPECIFICATION forming part of Design No. 26,060, dated September 22, 1896.

Application filed August 30, 1895. Serial No. 561,042. Term of patent 3½ years.

To all whom it may concern:

Be it known that I, HENRY A. WEIHMAN, a citizen of the United States, residing in the city and county of Philadelphia and State of Pennsylvania, have invented and produced a new and original Design for Handles for Nail-Files and Similar Articles, of which the following is a specification, reference being had to the accompanying drawing, which shows the design.

The leading feature of the design consists of the scroll-pattern and beaded edging about the edge of the handle of substantially the shape shown, the central portion of the handle being plain or unornamented.

As shown, the handle is of a modified elongated ovate shape with the opposite sides curved inward to form an attenuated portion A between the rounded ends B and C, of which the outer end B is the larger.

D is a small scroll-pattern at the smaller or inner end of the handle, and E is a larger scroll-pattern at the outer or larger end.

F F are lines of pearl-shaped beading extending along the side edges of the handle. 25 The central portion G is plain.

Having now described my invention, what I claim as new, and desire to secure by Letters Patent, is—

The design for the handle of nail-files and 30 similar articles, substantially as herein described and shown.

In testimony whereof I have hereunto set my hand this 19th day of August, 1895.

HENRY A. WEIHMAN.
